ATTORNEYS

UNITED STATES PATENT OFFICE.

HENRY CARLTON DIXON, OF TULSA, OKLAHOMA.

TAILOR'S ORDER-BLANK.

1,339,693.

Specification of Letters Patent. Patented May 11, 1920.

Application filed June 13, 1919. Serial No. 303,836.

To all whom it may concern:

Be it known that I, HENRY CARLTON DIXON, a citizen of the United States, and a resident of Tulsa, in the county of Tulsa and 5 State of Oklahoma, have invented certain new and useful Improvements in Tailor's Order-Blanks, of which the following is a specification.

My invention is an improvement in 10 tailors' order blanks, and has for its object to provide a blank of the character specified which, in addition to a complete record of the customer's measurements, will furnish one or more photographic views of the customer, in order that the tailor may have 15 before him a photograph showing the physical peculiarities of the customer.

In the drawings:

Figure 1 is a front view of the improved 20 blank;

Fig. 2 is an edge view.

In the present embodiment of the invention, a series of originals and a series of 25 duplicates is provided, the said series being arranged in alternating order, and the printed matter upon the originals 1 and duplicates 2 is the same, being the measurements for the coat, vest, trousers and over-coat.

30 Referring to Fig. 1, it will be noticed that each original is of greater length than the duplicate, being extended beyond the duplicate at the upper end thereof as indicated at 3, and each original has a transverse line 35 4 of partial separation, just below the upper end of the adjacent duplicate. Preferably the duplicates are secured to the rear faces of the originals just above the line 4, and the lower portion of the original, that 40 is, that portion below the line 4 and which carries the written measurements, may be detached from the duplicate.

45 Referring to Fig. 1, it will be seen that that portion of the original below the line 4 is provided with a space 5 having blanks for the coat measurements, a space 6 having blanks for the vest measurements, and a space 7 having blanks for the trousers measurements. In addition, there is another 50 space 8 which carries blanks for remarks and for overcoat measurements. It will be understood that the adjacent face of the duplicate is provided with similar spaces carrying similar blanks and similar printed matter. 55 The measurements set forth on the spaces 5,

6, and 7 and 8 are the usual measurements for this purpose.

That portion 3 of the original, namely, the portion above the line 4, is designed to carry a photograph of the customer, namely, 60 a back view and a side view. It is obvious that additional views might be provided for if desired, as, for instance, a front view. It is thought, however, that two views will be sufficient. These views may be pasted or 65 otherwise secured upon the extension 3 and the spaces 9 and 10 for the said views have suitable legends for indicating their purpose, the said legends in the present instance being "Back view" and "Side view". 70

In use, the measurements are made in the usual manner, and are entered on the original, a sheet of carbon paper being interposed between the original and the duplicate in order that the entries on the original 75 will be duplicated on the duplicate. The two views of the customer are taken and pasted on the spaces 9 and 10. After this has been done that portion of the original below the line 4 may be separated and retained as a 80 record, the duplicate with the photographs being sent to the mail order house or wherever else desired. If desired, the spaces 9 and 10 of the original may be sensitized in order that the photographs may be printed 85 directly thereon. In this case the portion 3 of the original would be folded upon the line between the spaces 9 and 10 and the edges would be sealed to prevent the entrance of light until after the printing from 90 the negatives.

The blank is especially designed for the use of traveling or resident salesmen for houses in other cities, and for agents of 95 mail order houses, and for orders for mail order houses to be filled by the customer.

The improved blank may be used to assist in properly altering clothing. For instance, should there be a wrinkle at any point, this point may be exactly indicated on the picture. It will be understood that as a rule a tape measure or tape line or ruler will be taken in the picture at the same time as the picture of the customer, in order to obtain a scale of measurement. It may be found 100 advisable, in practice, to take the customer's picture at the time the measurements are taken. These may be taken in a roll or pack. When taken, the films are properly identified, and may be attached to the blanks 105 110

and afterward developed to obtain the picture. The arrangement is as suitable for use in ladies' garments as in men's garments.

I claim:

- 5 1. An order blank of the character specified comprising an original and a duplicate, the original extending beyond the duplicate at its upper end and having a transverse line of partial separation below the upper end of the duplicate, the duplicate being attached just above the transverse line of partial separation, that portion of the original below the line and the duplicate having corresponding data printed thereon, indicating 10 the measurements of the customer, that portion of the original below the line being

adapted to be separated from the remainder after it has been filed to furnish a record, while the remaining portion is forwarded for the filling of the order.

20

2. An order blank of the character specified comprising an original and a duplicate, the original extending beyond the duplicate at its upper end and having a transverse line of partial separation below the upper end of the duplicate, the duplicate being attached just above the transverse line of partial separation, that portion of the original below the line and the duplicate having corresponding data printed thereon, indicating 25 the measurements of the customer.
